UNITED STATES PATENT OFFICE.

JAMES A. MCPHERSON, OF BRUNSWICK, NEW YORK.

TORCH.

SPECIFICATION forming part of Letters Patent No. 299,411, dated May 27, 1884.

Application filed December 29, 1883. (No model.)

To all whom it may concern:

Be it known that I, JAMES A. MCPHERSON, a resident of Brunswick, in the county of Rensselaer and State of New York, have invented certain new and useful Improvements in Torches; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in torches; and it consists in providing a torch frame or staff with a single arm, one end of the latter being pivoted to one end of the former, and adapted to support upon its swinging end a torch-bowl loosely suspended therefrom at a point or points above its center of gravity, also with a link by which three or more frames may be fastened together, and in forming the arm, link, and pivot-socket of a single piece of wire.

The objects of my invention are, first, to provide a swinging torch attached to a frame or staff by a single arm in such a manner that the torch-bowl will always assume a vertical position in whatever position the staff is held; second, to provide a hook-link or its equivalent at or near the torch-bearing end of the staff, for stacking three or more torches in a manner similar to that in which muskets are stacked; third, to provide a pivoted torch-bearing arm, pivot-socket, and stacking-link, all made from a single piece of wire, thereby cheapening the construction of torches.

Figure 1 of the drawings is a side elevation. Fig. 2 shows a modified form. Fig. 3 is a plan view of three torches and frames stacked together.

A represents a torch-bowl, provided with one or more tubes and wicks, E, for illuminating purposes, and with a link, a, adapted to receive and swing upon the hook b at the end of arm C, which arm is pivoted upon the staff or frame B by means of the socket G and pin or mandrel P, driven into the end of the staff, as shown by the dotted lines.

The socket G, as shown in Fig. 1, is composed of several coils of the wire, which forms the arm C at one end and at the other the link D, which latter serves to fasten the torches together when it is desired to stack them. Instead of wire, sheet metal or any desired material may be used to form arm C, socket G being formed by bending one end upon itself and riveting it, as shown in Fig. 2, in which only the upper portion of the torch is shown.

The link D' would be preferably made of a separate piece, as shown, and pivoted upon pivot P; or it may be hung from staple c, driven into the staff, as shown.

Torches such as I have described are principally used in parades during political campaigns, and carried by the staff in the same manner as muskets are carried in military parades, the torch occupying the relative position of the bayonet. It is important, therefore, not only that the torch-bowl should be arranged to assume a vertical position in whatever position the staff is carried, but that the construction should be simple, light, and cheap, rather than heavy and durable, their use being limited to a very short period. It is also important that some attachment—such as link D, or its equivalent—should be provided, by which the torches can be stacked in triplets, like muskets, as shown in Fig. 3, thereby preventing the necessity of laying the torches upon the ground when the owner is at rest or temporarily off duty, when they are likely to be tipped over, lost, or broken, as frequently happens.

By employing a single supporting-arm passing through a link attached to the central portion of the top of the torch-bowl, the whole of the bowl and contents are below the point of support, and a vertical position is more quickly assumed and readily maintained, and less material is required in construction than when two arms are employed, as has been the practice heretofore. As the supporting-arm C projects to one side of the pivot P when the staff is in a vertical position, any revolution of the staff when in an inclined position will not change the position of the supporting-arm or the torch-bowl.

The torches may be stacked in any desired manner; but I prefer to connect two torches by the links D, cross the staves B, and insert

15 a third torch-staff between the links and the crossed staves in such a manner that the connected links will rest upon the arm C of the third torch, the link of the latter projecting 20 out away from the connected links, as shown in Fig. 3. By employing only one supporting-arm C, instead of two, I can pack many more torches 25 in a given space for shipment in supplying the trade.

I am aware of Patent No. 188,332, of October 17, 1876, and I do not claim the construction shown in said patent, for the reason that in my invention I employ simply a single pivoted arm from which the torch is suspended 30 by a pivot at its top, whereby it is always held in a vertical position, while in the patent above referred to is shown an arm inserted into the shaft and then connected by a screw-joint to a two-prong fork to which the torch 35 is attached by side pivots, which makes the device more complicated and expensive than in the construction of my torch.

What I claim as new, and desire to secure by 40 Letters Patent, is—

1. In a torch, the combination of the staff, the single lamp-supporting arm projecting to one side of the staff and twisted to form an

45 eye, the pin passing through the eye into the staff to form a swivel, and a lamp pendent 50 from the projecting end of said arm, substantially as and for the purposes described.

2. A single torch-supporting arm, C, composed of wire bent to form the socket G and link D, both integral therewith, in combination 55 with pin P and staff B, substantially as described, and for the purposes set forth.

3. A torch staff or handle having a lamp-support pivoted thereon, in combination with a torch-lamp and a connecting-link, by which 60 two or more torches are linked together when stacked, substantially as described, and for the purposes set forth.

4. A torch-bowl provided with a central projecting link on its upper surface, by which 65 it is suspended from a pivoted support, in combination with said support and the staff or handle upon which the support is pivoted, substantially as described, and for the purposes set forth.

In testimony whereof I have hereunto set my hand this 24th day of December, 1883.

JAMES A. MCPHERSON.
